UNITED STATES PATENT OFFICE.

WILLIAM HENRY SAUVAGE, OF NEW YORK, N. Y., ASSIGNOR TO SAUVAGE WARD BRAKE COMPANY, INC., A CORPORATION OF DELAWARE.

AUTOMATIC SLACK-ADJUSTER FOR BRAKES.

1,120,090.

Specification of Letters Patent.

Patented Dec. 8, 1914.

Application filed December 14, 1912, Serial No. 736,690. Renewed October 27, 1914. Serial No. 868,899.

To all whom it may concern:

Be it known that I, WILLIAM H. SAUVAGE, a citizen of the United States, residing in the borough of Manhattan of the city of New York, in the county of New York, in the State of New York, have invented certain new and useful Improvements in Automatic Slack-Adjusters for Brakes, of which the following is a specification, reference 10 being had to the accompanying drawings, which form a part hereof.

This invention relates to automatic slack adjusters for railway brakes and has for its object to improve generally the construction 15 of the same.

The invention relates particularly to slack adjusters in which the take-up device is mounted on the car body so that its parts are not subject to operation by reason of 20 the movement of the truck bolster about the king bolt.

One object of the invention is to arrange the moving parts of the take-up device more compactly than hitherto so that they may 25 be incased and protected from the elements.

Another object is to provide means in operative relation to the slack adjuster and disposed within easy reach of the operator, so as to avoid the necessity of getting under 30 or between the cars, to permit the take-up members to be released manually thus freeing, to a maximum degree, the entire truck brake rigging.

Still another object is to provide positive 35 means for returning the brakes to release position, which means may or may not co-operate directly with the take-up devices.

A further object is to introduce between the take-up device and the brake rigging adjustable means for determining readily the extent of free travel of the brake actuating mechanism prior to the actuating of the slack adjusting members. In accordance 40 with the invention this last named means is of a simple nature and may be adjusted quickly by one man with the aid of ordinary tools.

Another object is to mount the usual dead lever in such a position that it will not 50 come into contact with the truck bolster and that too though the latter assumes its maximum angular relation with the transverse axis of the car. This construction eliminates the danger previously caused by the

shifting of the fulcrum of the dead lever 55 and the corresponding lessening of the clearance of the brake shoes.

The manner in which these and other objects are attained will appear hereinafter, reference now being had to the accompanying 60 drawings in which—

Figure 1 is a view partly in longitudinal section and partly in elevation, showing a conventional form of truck and a portion of the car body with one form of the means 65 for adjusting automatically the fulcrum of the dead lever. Fig. 2 is a view in vertical section of the take-up device shown in Fig. 1, but on a larger scale. Fig. 3 is a view taken on the plane indicated by the line 70 3—3, Fig. 2. Fig. 4 is a detail view on an enlarged scale of a modified form of a release spring between the pull rod and the take-up rod. Fig. 5 is a view similar to that of Fig. 1 with the parts of the take-up device so modified that the torsional spring 75 thereof shall serve also as the release spring. Fig. 6 is a view similar to that of Fig. 2 showing the take-up device employed in Fig. 5. Fig. 7 is a view taken on the plane 80 indicated by the line 7—7 of Fig. 6. Fig. 8 is a view taken on the plane indicated by the line 8—8 of Fig. 6.

As shown in Figs. 1 and 5 the car body *a* is supported upon the body bolster *b* which 85 in turn is supported upon the truck bolster *c* through the usual king bolt *b'*. Springs *c'*, carried by a suitable rigid portion of the truck frame, support the truck bolster *c*. Upon the sand plank *d* are hung the brake 90 shoes *e* with the brake beams *e'*, the latter being connected as usual by struts *e''* to the dead lever *f* and the live lever *f'*. The two levers are connected as usual by the bottom rod *f''* while the live lever *f'* is connected to 95 the top rod *f'''* of the brake actuating mechanism, which may be of any approved design and either hand or power operated.

The dead lever *f*, as before indicated, is provided with an adjustable or shiftable 100 fulcrum positioned automatically to take up wear on the brake shoes and all lost motion or slack resulting from wear on any of the connections or other parts of the brake rigging. In the construction shown, the upper 105 end of the dead lever *f* is connected operatively to a sheave *g* by a flexible connection *g'*, herein shown as a chain. The free end

of this chain is attached to the sheave in any suitable manner and lies in a circumferential groove with which the sheave is preferably provided. It should be noted here that the point of attachment of the chain g' to the sheave g is such with regard to the extreme travel thereof permitted by the brake rigging that the chain can never encircle completely the periphery of the sheave. This is important when the fulcrum of the dead lever is shifted automatically to compensate for the wear on the brake shoes as will appear later. Mounted in juxtaposition to the sheave g in the construction shown in Figs. 1-4, is a second sheave i the two lying in a casing h which is attached rigidly to the car body in any suitable manner, as by lugs h' fastened to depending angle irons a' . The second sheave i is mounted rotatably on a suitable axle h^2 extending transversely through the casing h and supported by the walls thereof. The sheave i preferably is provided with a peripheral groove in which is disposed a flexible connection i' such as a chain, attached thereto by a suitable stud i^2 and having its outer end connected to a take-up rod i^3 which extends longitudinally under the car body a and has a depending yoke i^4 at its outer end through which passes the pull or top rod f^3 of the brake actuating mechanism. Between the yoke i^4 and an adjustable abutment f^4 on said top rod f^3 , herein illustrated as a sliding clamp, is a spring j adapted to be compressed upon the operation of the brakes. This spring, hereinafter termed the release spring, operates upon the release of the brake actuating mechanism to force the brakes into their full release position.

Referring now to Fig. 2 it will be seen that the sheave i is recessed internally and has disposed therein a spring k which has one end anchored in the casing h and the other end anchored in the sheave, whereby rotation of the latter on its axis h^2 is resisted. It should be noted here that in the construction now being described, the spring k is of greater tension than the spring j for a reason which will appear later. The sheave i is provided at one side with an annular extension or boss of lesser diameter than the sheave and on which is rotatably mounted the other sheave g . The relative dimensions of the different portions of the two sheaves is immaterial, save that it is important that their circumferential lengths be equal for a reason that will appear hereinafter.

On the inner face of the take-up sheave g is formed an annular boss g^2 provided on its periphery with ratchet teeth g^3 adapted to be engaged by a spring pressed pawl i^5 carried on the inner face of the sheave i . The pawl runs freely over the teeth when the

sheave i turns in a counter-clockwise direction but engages operatively therewith when said sheave rotates in a clockwise direction. In the latter case corresponding movement is, of course, imparted to the take-up sheave g . To prevent positively rotation of the latter in a counter-clockwise direction when subjected, during the application of the brakes, to strain the greater part of which is transmitted through the dead lever f , a dog l is mounted on the casing h and has teeth l' in engagement with the ratchet teeth g^3 . This dog is of very substantial construction since it receives practically the entire force of application of the brakes to the wheels. As shown best in Fig. 3 the dog l prevents counter-clockwise rotation of the sheave g while permitting free movement in the opposite direction, the weight of the dog being sufficient to keep the teeth in engagement with the rack. As indicated in Figs. 1 and 5 and illustrated in detail in Fig. 7 the handle of the dog l may be operatively connected to a rock shaft l^3 as by link members l^4 , permitting movement of the dog independently of the rock shaft. The rock shaft l^3 may be mounted in suitable brackets l^5 on the under side of the car body and extends entirely across the same. On each end of the rock shaft l^3 may be secured operating levers l^6 disposed within convenient reach of the operator so that the dog l may be operated from either side of the car and that too, without the necessity of the operator getting under the car body or between the cars.

In the operation of the brakes the upper end of the dead lever f is held stationary by reason of the engagement of the dog l with the ratchet teeth g^3 of the sheave g and the connection between the sheave g and the fulcrum of the lever. The upper end of the live lever f' , however, is moved toward the left, in Fig. 1, forcing the stop f^4 against the release spring j and thereby compressing the latter. This spring is not itself of sufficient strength to move the rod i^3 against the tension of stronger spring k in the sheave i . The stop f^4 is adjusted on the rod f^3 so that during normal operation of the brakes, its travel will be just sufficient to compress completely the spring j so that the adjacent coils thereof abut. In practice such travel is usually about four inches before the spring is compressed solidly. When the brake shoes have worn, a longer travel of the top rod f^3 will be necessary, so that upon continued movement of the stop f^4 the tightly compressed spring j will serve as a solid abutment and transmit movement to the reach rod i^3 . This movement will in turn be imparted to the sheave i which will be rotated counter-clockwise, the pawl i^5 riding freely over the ratchet teeth g^3 of the sheave g . When the brakes are released

the sheave i will be returned to its normal position under the action of the torsional spring k and the pawl i^s , engaging with the teeth g^s , will rotate the sheave g a distance circumferentially equal to that through which sheave i was displaced, which distance is equal to the excess travel of the brake shoes. Since the circumferential length of the two sheaves is equal and since their respective connections to the dead and live levers are tangential to their peripheries, it will appear that the upper end of the dead lever will be moved to the right by the take-up sheave g a distance equal to the excess travel of the brake leverage system thus coöperating automatically for wear of the brake shoes as well as for slackness caused otherwise.

It may be desirable to limit the degree of rotation of the sheave i and for this purpose stops h^s may be provided on the inner face of the casing h , which stops are adapted to be engaged by a lug i^s disposed in an annular groove formed on the inner face of the boss of the sheave i . These stops and lug may be so disposed relatively as to hold the sheave i in the same zero or set position under the action of the spring k while limiting the degree of rotation thereof during operation of the brakes.

When it is desired to release the brake shoes for the purpose of replacing them, the operator, simply grasps one of the handles l^s of the rock shaft l^s and by rocking the latter raises the dog l and thus throws the teeth of the dog out of engagement with the ratchet teeth g^s . In the construction shown, the dog l has a downward extension l^2 lying in juxtaposition to the tail of the pawl i^s so that the latter is disengaged from the teeth g^s simultaneously with the disengagement of the teeth of the dog. The sheave g may now rotate freely and the chain g' be paid out, fully releasing the brakes.

It should be emphasized here that the brake rigging is so positioned with respect to the dead lever f that the upper end of the latter may never come in contact with the truck bolster c . A glance at Fig. 5 will show readily that if the truck bolster swings about the king bolt b' , as it does on a curve, it cannot contact with and force the upper end of the dead lever f to the right so that the fulcrum thereof will be changed.

It will be obvious that the release spring j when provided as a separate element may be placed in other positions relative to the top rod f^s and the reach rod i' , although it will appear hereinafter that the torsional spring k and release spring j may be constructed as one member while performing the distinct functions of the two springs referred to. In Fig. 4 is shown a modification in structure hereinbefore described.

There the reach rod is made in two sections i^s and i^o connected respectively to the sheave i in the manner before pointed out and operatively to the live lever f' as by means of a clamp i^{15} and bolts i^{16} shown in Fig. 5 70 and described hereinafter. Pivotally connected to one of these sections i^o is a yoke i^{10} encircled by a spring i^{11} one end of which is anchored to the yoke as at i^{12} . Against the free end of said spring is a suitable abutment or plunger i^{13} having recesses l^{14} to receive the yoke and being connected operatively to one section of the reach rod i^s . Relative movement of the two sections in opposite directions will compress the spring 80 as before explained, and continued compression will force the coils into contact to form a solid abutment and so operate the sheave i . By this modification this independent spring i^s will perform the function of a 85 release spring and return the brakes positively to their full release position.

Reference is now to be had to Figs. 5-8 in which the release spring, as an independent element, is eliminated, while the function 90 thereof is fully retained. In this construction the torsional spring hitherto described and which coöperates directly with the take-up devices serves not only to perform the function ascribed to it before, but also positively moves the brakes to full release position. In this dual capacity and for purposes of description, this spring may be considered first as a release spring and then as 95 a torsional take-up spring.

The description of those principal parts in Figs. 1-4 which are employed in the same capacity in the structure now to be described will suffice and need not be repeated, all of such parts being designated throughout 100 by the same reference characters. In some instances, however, the shape of certain parts or the relationship thereof to other elements has been changed and such modified parts will be designated by different reference 105 characters.

Referring now to Fig. 5 it will be seen that the reach rod i^s is provided at its outer end with a depending clamp i^{15} which is preferably attached thereto pivotally by means of a bolt i^{16} . The clamp i^{15} embraces the top or pull rod f^s and may be secured adjustably thereto for a purpose before described in connection with the clamp f^s . The inner end of the reach rod i^s is secured in the manner before described, to a sheave i^{17} rotatably mounted on the axle h^s and having a boss i^{18} on which is rotatably mounted the take-up sheave g . A spring m is disposed within an interior recess i^{19} in the sheave i^{17} and has one end secured to the casing h and the other end secured to the sheave whereby rotation of the sheave in a counter-clockwise direction is opposed. On the inner face of the sheave i^{17} is formed 110

115

120

125

130

an arcuate groove i^{20} of a length equal to the normal travel of the brake shoes, for a purpose to be pointed out later.

- 5 Rotatably mounted on the boss g^4 of the sheave g and disposed between the sheave i^{17} and the take-up sheave g is an annular disk n having a stud n' on one of its faces, disposed within the arcuate groove i^{20} of the first named sheave. On the face contiguous to the sheave g , the disk n has secured a spring pressed pawl n^2 normally in engagement with the ratchet teeth g^3 of the disk g , as described with reference to the pawl i^3 shown in Fig. 3.
- 15 Referring now to Fig. 8, it will be seen that when the brakes are released and the sheave i^{17} is held in zero position under the action of the torsional spring m , the arcuate groove i^{20} is so disposed with respect to the stud n' as to permit free rotation of the sheave i^{17} in a counter-clockwise direction when the brakes are applied, without causing corresponding rotation of the disk n through the engagement of the end of the groove with the stud. After the groove and the stud have moved relatively a distance equal to the length of the groove, however, the end of the groove and the stud will come in engagement. In case of excess travel of the brake due to wear or lost motion in the rigging, continued rotation of the sheave i^{17} will occur, as well as corresponding rotation therewith of the disk n . Rotation of the disk n will carry the pawl n^2 over the ratchet teeth g^3 a distance equal to the excess travel of the pull rod f^3 , as will be understood from the description hereinbefore given. Immediately upon the release of the brakes, the spring m , acting as a release spring, will move the sheave i^{17} with respect to the stud n' , a distance equal to the length of the arcuate groove i^{20} and simultaneously will move the brakes to their full release position. Continued movement of the sheave i^{17} will then follow under the action of the spring m , as a take-up spring, for a distance equal to the excess travel of the pull rod on the preceding application of the brakes. This movement will be transmitted to disk n through the engagement of the end of the arcuate groove i^{20} with the stud n' . Movement of the disk n will serve to move to a corresponding extent the sheave g through the engagement of the pawl n^2 with the ratchet g^3 and thus move the fulcrum of the dead lever f a distance equal to the excess travel of the pull rod, all as pointed out with respect to the structure shown in Figs. 1-4.
- 60 Except for the differences specifically pointed out, the take-up devices and co-operating elements are similar structurally in all of the figures of the drawings, it being understood, however, that modifications in detail of structure, such as would suggest

themselves to a skilled mechanic, may be made in any or all of the forms herein shown, without departing from the scope of the invention.

What I claim is:

1. The combination of a car body, a truck, a brake system comprising a live lever and a dead lever, an automatic take-up device mounted on the car body and including two relatively rotatable members operatively connected one to the live lever only and the other to the dead lever only and means connected to the take-up device to release and move the brakes to full release position. 70

2. The combination of a car body, a truck, a brake system comprising a live lever and a dead lever, and an automatic take-up device mounted on the car body and comprising two sheaves connected operatively to the live lever and to the dead lever respectively, 85 one of said sheaves being rotated with respect to the other by excess travel of the pull rod, and clutch means interposed between said sheaves to lock the same during reverse rotation of said first named sheave. 90

3. The combination of a car body, a truck, a brake system including a live lever and a dead lever, and an automatic take-up device mounted on the car body and comprising two sheaves connected operatively to the live lever and to the dead lever respectively, 95 one of said sheaves being rotated with respect to the other by excess travel of the pull rod, means interposed between said sheaves to lock the same during reverse rotation of said first named sheave and means to cause automatically the reverse rotation of said first named sheave upon release of the brakes. 100

4. The combination of a car body, a truck, 105 a brake system comprising a live lever and a dead lever and an automatic take-up device mounted on the car body and comprising two sheaves connected operatively to the live lever and to the dead lever respectively, one of said sheaves being rotated with respect to the other by excess travel of the pull rod, means interposed between said sheaves to lock the same during reverse rotation of said first named sheave, and 110 means incased in said first named sheave to cause automatically the reverse rotation thereof upon release of the brakes. 115

5. The combination of a car body, a truck, a brake system comprising a live lever and 120 a dead lever, and an automatic take-up device mounted on the car body and comprising two sheaves connected operatively to the live lever and to the dead lever respectively and means engaging the second named of 125 said sheaves to prevent positively rotation thereof in one direction while permitting free movement thereof in the opposite direction and operable manually to release said sheave entirely. 130

6. The combination of a car body, a truck, a brake system comprising a live lever and a dead lever, and an automatic take-up device mounted on the car body and comprising 45
 5 two sheaves connected operatively to the live lever and to the dead lever respectively, means engaging the second named of said sheaves to prevent positively rotation thereof in one direction while permitting free 50
 10 movement thereof in the opposite direction and manually operable means disposed at one side of the car body and connected to said last named means to release the second 55
 15 named sheave entirely.
7. The combination of a car body, a truck, a brake system comprising a live lever and a dead lever, and an automatic take-up device mounted on the car body and comprising two sheaves of equal circumferential 60
 20 length mounted concentrically and operatively connected to the live lever and to the dead lever respectively, one of the sheaves being rotated in one direction by excess travel of the pull rod, means to prevent rotation 65
 25 of the other sheave in the same direction, said means permitting free movement thereof in the opposite direction, means to rotate the first named sheave in the reverse direction and a clutch operable upon said 70
 30 reverse rotation to connect said sheaves whereby the fulcrum of the dead lever is moved a distance equal to the excess travel of the pull rod.
8. The combination of a car body, a truck, 75
 35 a brake system comprising a live lever and a dead lever, a casing mounted on the car body, and an automatic take-up device comprising two sheaves mounted in said casing, one of said sheaves being connected operatively to the live lever and adapted to be moved by excess travel thereof and the other of said sheaves being connected to the dead lever, a spring disposed within the 80
 40 first named sheave to resist rotation thereof by excess travel of the pull rod, a rack carried by the other sheave, a dog mounted on the casing and engaging the rack to prevent rotation of said sheave during movement of the first named sheave caused by excess travel of the pull-rod but permitting free 85
 45 movement thereof in the opposite direction, a spring pressed pawl carried by the first named sheave and engaging the rack whereby the two sheaves are rotated together under the action of said spring when the 90
 50 brakes are released and means carried by the casing to limit such last named movement whereby the fulcrum of the dead lever is moved a distance equal to the excess travel of the pull rod.
9. The combination of a car body, a truck, a brake system comprising a live lever and a dead lever, and an automatic take-up device mounted on a car body and including two sheaves of equal circumferential length 60
 55 mounted concentrically and operatively connected to the live lever and to the dead lever respectively, one of the sheaves being operated in one direction by excess travel of the pull rod, means to prevent rotation of the other sheave in the same direction, said means permitting free movement thereof in the opposite direction, means to rotate the first named sheave in the reverse direction, an annular disk interposed between 70
 60 said sheaves and permitting free relative movement of said sheaves for a limited distance in one direction and operable upon reverse rotation of the first named sheave to connect said sheaves whereby the fulcrum 75
 65 of the dead lever is moved a distance equal to the excess travel of the pull rod.

This specification signed and witnessed this 9th day of December A. D., 1912.

WILLIAM HENRY SAUVAGE.
